UNITED STATES PATENT OFFICE.

GEORGE W. J. CRABB, OF NEWARK, NEW JERSEY.

LUBRICATING DEVICE.

1,262,022.

Specification of Letters Patent.

Patented Apr. 9, 1918.

Application filed August 1, 1917. Serial No. 183,824.

To all whom it may concern:

Be it known that I, GEORGE W. J. CRABB, a citizen of the United States, residing at Newark, in the county of Essex and State 5 of New Jersey, have invented a new and useful Improvement in Lubricating Devices, of which the following is a specification.

My invention relates to improvements in 10 lubricating devices designed especially for use in lubricating car wheels and the flanges thereof. The object of my invention is to provide a device which may be controlled by the operator of the car or train to the 15 wheels of which my device is attached, and which may thus be used to lubricate the wheel flanges when the car or train is moving on curves, thus preventing noise and wear. Other objects and advantages of my 20 invention will appear more fully hereinafter.

The preferred embodiment of my invention is illustrated in the drawings accompanying and forming a part of this specification. Referring to the drawings,—

Figure 1 is a side view of my lubricating device;

Fig. 2 is a vertical section of the lubricant tank;

Fig. 3 is a horizontal section view of the structure shown in Fig. 1;

Figs. 4 and 5 are views of my device as it appears when attached to the car, the wheels of which are to be lubricated, Fig. 35 4 being a view from above and Fig. 5 a side view.

Similar numbers refer to similar parts throughout the several views.

My device comprises a frame 1, and a tank 40 2, the latter being mounted on two rods 3 slidably mounted in the frame 1. These rods pass through the cores of two electromagnets 5, which are placed between the vertical members 6 and 7 of the frame 1. 45 An armature 4 is mounted on the ends of the rods 3 and is adapted to be drawn in by the magnets 5 and thus to force the tank outwardly when the magnets are energized. The rods and tank are held in normal position by the pressure of the springs 8, which bear at one end against the vertical member 9 of the frame 1, and at their other end against the collars 10, rigidly fastened to the rods 3 by means of set-screws or otherwise. 50 These collars 10 normally rest against the member 6 of the frame. The tank 2 is

designed to hold a lubricant 11 of any approved kind, into which two wicks 12 extend. The wicks pass out of the tank through two guides or tubes 13, which are so bent, 60 at their outer extremities, as to approach one another. The wicks are adjusted to project slightly beyond the outer ends of the tubes, and means 14 may be provided to facilitate such adjustment.

The whole device, 18, as above described, is then attached to the truck or other part of the car so that the ends of the wicks will be adjacent to the flange of the wheel to be lubricated, as shown in Figs. 4 and 5; that 70 is to say, the outer ends of the wicks 12 will be disposed one on each side of the flange 15 of the wheel 16.

One of my improved lubricating devices is preferably located at each wheel of the 75 car or train and leads are carried from each to a common switch or push-button located adjacent the engineer or motorman, so that he can, on approaching or going around a curve, energize the magnets and thus cause 80 all of the flanges to be lubricated. The lubricant will continue to be applied so long as the switch or push-button is held in closed position. When opened, the magnets are deenergized and the springs 8 restore the 85 device to an inoperative position.

While I have described only the preferred embodiment of my improved device, I am aware that various modifications in detail and in the arrangement and combination of 90 the parts may be made by those skilled in the art without departure from my invention, and I desire protection for all such modifications as come within the scope of my claims.

Having described my invention, what I 95 claim is:—

1. A car-wheel lubricating device comprising in combination a lubricant reservoir mounted on the car and movable in a plane 100 perpendicular to the axis of rotation of the wheel to be lubricated, and means associated with said reservoir for applying lubricant to the wheel flange.

2. A car-wheel lubricating device comprising in combination a lubricating member supported by the car and arranged to move in a plane at right angles to the axis of revolution of the wheel to be lubricated, and means whereby said lubricating member may be thrown into contact with the 110 flange of the wheel.

3. A car-wheel lubricating device comprising in combination a lubricant reservoir, a pair of wicks associated with said reservoir, and operator controlled means whereby said wicks may be thrown against the wheel flange to be lubricated, one against each side thereof.

4. A car-wheel lubricating device comprising in combination a lubricant reservoir mounted to move in a plane perpendicular to the axis of rotation of the wheel to be lubricated, a pair of wicks supported from

said reservoir, and means whereby said reservoir may be moved to throw said wicks against the flange of the wheel, said wicks being arranged to contact with both sides of the flange.

5. A car-wheel lubricating device comprising in combination a reservoir, movable rods on which said reservoir is supported, coils through which said rods extend, and a bar armature connecting the ends of said rods.

GEORGE W. J. CRABB.

Copies of this patent may be obtained for five cents each, by addressing the "Commissioner of Patents, Washington, D. C."

It is hereby certified that in Letters Patent No. 1,262,022, granted April 9, 1918, upon the application of George W. J. Crabb, of Newark, New Jersey, for an improvement in "Lubricating Devices," an error appears in the printed specification requiring correction as follows: Page 2, line 4, claim 3, strike out the words "operator controlled"; and that the said Letters Patent should be read with this correction therein that the same may conform to the record of the case in the Patent Office.

Signed and sealed this 11th day of June, A. D., 1918.

[SEAL.]

F. W. H. CLAY,
Acting Commissioner of Patents.
